CLAIM

The ornamental design for a miniature solar disco ball, as shown and described.

DESCRIPTION

FIG. 1 is a front elevational view of the miniature solar disco ball showing my design;

FIG. 2 is a rear elevational view thereof;

FIG. 3 is a top plan view thereof;

FIG. 4 is a bottom plan view thereof;

FIG. 5 is a front perspective view thereof; and,

FIG. 6 is a left sided elevational view thereof, the side opposite being a mirror image.
